UNITED STATES PATENT OFFICE

2,598,310

ADJUSTABLE STAND LAMP WITH A SWITCH
AND A HANDLE TO ADJUST THE LAMP
AND ALSO ACTUATE THE SWITCH

George Schaser, Gary, Ind.

Application March 8, 1950, Serial No. 148,345

3 Claims. (Cl. 240—81)

1

This invention relates to a novel adjustable stand lamp with a switch and a handle to adjust the lamp and also actuate the switch.

With the use of the familiar electric standing lamp, and more particularly the ordinary type of floor lamp which includes a standard having a bracket arm adjustably mounted thereon and carrying the usual light bulb and lamp shade, and which is customarily placed alongside an easy chair used for reading purposes, it is well known that when it is desired to adjust such bulb and shade, especially by the occupant of such chair, the shade is generally grasped by the hand in making the desired adjustment. Furthermore, in grasping and actuating the short chain of the pull-chain switch, often provided on such a lamp, the shade is frequently touched by the hand. Such touching and handling of the shade quickly mars and soils the same, which then soon requires cleaning thereof or even replacing the same by a new one.

It is an essential object of this invention, in its broad or comprehensive aspect, to provide a novel control device for an electric lamp of this kind, wherein this device includes means arranged and positioned to be conveniently engaged by the hand and readily actuated for adjusting the lamp bulb and shade into the desired position, and without any need of grasping or soiling the shade.

A further object of this invention is to provide in such an electric standing lamp novel control means comprising an operating element that is placed near the lower part of the lamp shade and is thus readily grasped by the hand of the occupant of a chair adjacent said lamp, whereby to adjust the position of the lamp bulb and shade without handling the shade.

A more particular object of this invention is to provide such a control device for use on a well known type of electric standing lamp which has its bulb-socket equipped with a pull-chain switch, and wherein this device comprises a handle arranged to engage such pull-chain, and to be readily operated for actuating said chain and switch as well as for adjusting said socket with its bulb and shade.

Another object of this invention is to provide a novel electric lamp control device which is arranged and constructed so as to be readily interposed between the upright standard and the bulb-carrying socket of the customary standing lamp, and can thus be conveniently substituted for or take the place of the present socket-carrying bracket-arm that has so far been used between said standard and socket, whereby to in-

2

duce economy in the cost of such a lamp equipped with this control device.

These and various other objects and advantages are attained with this invention, as will become apparent from the following description, taken in connection with the accompanying drawings wherein it is shown in a few of its various forms, it being evident that other arrangements and forms of construction may be resorted to in carrying out the objects and purposes of this invention.

In the drawings:

Fig. 1 is a side elevational view of a floor lamp, including the customary standard, partly broken away, which is equipped with my novel control device shown in a preferred form.

Fig. 2 is a similar elevational view, showing my invention in another form and mounted upon the standard of such a lamp.

Fig. 3 is an enlarged detail section, taken on line 3—3 of Fig. 1, of the first said form and looking upwards.

Fig. 4 is an enlarged elevational detail view, taken on line 4—4 of Fig. 1.

Fig. 5 is a vertical sectional view, taken on line 5—5 of Fig. 4, and illustrating the construction of the sleeve and connected control rod and handle of this first form.

Fig. 6 is a vertical section view thereof, taken on line 6—6 of Fig. 5.

Fig. 7 is a horizontal sectional view, on line 7—7 of Fig. 4.

Fig. 8 is a side elevational view showing this invention in another form and applied onto a known lamp standard.

This invention is illustrated in the drawings in a few of its several slightly varying forms of construction, all of which are adapted for use on a well known type of electric standing lamp, indicated in Fig. 1 in the shape of a floor lamp 10 which includes the usual form of hollow standard or upright post 11 that arises from a base 12 and is arranged to contain an electric conductor therein, as is indicated at 13 in Fig. 1, in the usual well known manner. In the three forms as disclosed herein, as variously shown in Figs. 1, 2 and 8, each comprises my novel control device 14 which is arranged to be readily mounted upon such a lamp standard 12 and which can be conveniently engaged by the hand for adjusting the lamp upon the standard.

In Fig. 1 and detail views, partly in section Figs. 3, 4, 5, 6 and 7 this invention is shown in a very complete and desirable form, wherein my control device 14 comprises an arm or tubular bracket member 15 which has a casing or

head 16 attached to one end that contains a depending stem or tubular neck 17 thereon arranged to fit rotatably into the top end of said standard, whereby this device is thus readily but detachably mountable on the standard for swingable adjustment thereon in a substantially horizontal plane. Said head 16 included herein is substantially in the shape of a switch box carrying therein the well known form of snap-switch 18 which includes a pull-chain 19 to actuate it and which is operably connected with such electric conductor 13, while a conductor part 13' is extended from said switch 18 and conductor 13 thru the arm 15, in the usual manner.

The tubular member or arm 15 contains on its outer or free end a member 21 arranged to receive and carry thereon the customary lamp supporting socket; and this member 21 is preferably in the form of a sleeve as disclosed herein, and a knuckle 22 is provided on the end of arm 15 whereon this sleeve is adjustably mounted, as by means of screws 23 extending thru the sleeve into the knuckle. The sleeve can thus be tilted on the knuckle, as indicated in Fig. 2, and can be readily adjusted thereon in a substantially vertical plane. A spring 24 is seated in the sleeve and carries a segment 25 on its upper end to hold it frictionally against the knuckle 22, whereby to retain this sleeve in its adjusted position.

This novel member or sleeve 21 has a threaded stem 26 depending from its lower end, and this stem is arranged like the usual stem on a known electric lamp bracket, for receiving and supporting thereon the customary electric switch 27 with its pull-chain 28 and containing the socket part 29 for receiving and carrying therein the bulb 30 and also the shade 31 thereon, as indicated in Fig. 1 of the drawings. Said sleeve 21 has the hand-engaged control means 32 attached thereto for adjusting the position of the lamp; and in this form is also arranged for actuating the switch 27. This is preferably accomplished by means of a depending element or rod 33 which has its upper end 34 bent over and beveled to fit tightly into a pocket 35 provided on the side of the sleeve 21, and said rod has a knob or handle 36 with a bore 37 therein slidably mounted and frictionally held on its lower end. A notch, Figs. 5 and 6, 38 provided in a cap 39 on the handle 36 is arranged to receive therein the lowest bead of said pull-chain 28; so that by simply engaging and slightly moving or sliding this handle 36 on the rod 33 the switch can be conveniently actuated, and at the same time as you adjust the socket with its bulb and shade hereby; and all of this can be conveniently accomplished by an occupant of a chair positioned alongside this lamp, without any need of handling the shade or soiling its visible exterior.

In Fig. 2 this invention is illustrated as comprising a modified hand-engaged means 32'', and this form is more particularly adapted for use where its switch member 27'' with its attached lamp-socket 29'' is not equipped with a pull-chain switch, like that shown in Figs. 1 and 8. Otherwise, the parts herein are identical with those first above described and comprising the bracket arm 15 having at one end the casing 16 with its pull-chain switch 18 and depending stem 17 for mounting the device swingably upon the customary lamp standard 11; said arm also carrying on its outer end the sleeve 21, tiltably adjustable on screws 23, and

5 containing thereon the pocket 35 and also the depending stem for having attached thereto said chainless switch member and socket, 27'' and 29''. Altho herein the rod 33'' is bent and beveled at its upper end and fits tightly but removably in that pocket 35, just as in the other forms, yet herein the handle or knob 36'' with the connected end of said rod are modified and are preferably arranged to be held firmly together, as by the use of interengaging threads as indicated; since herein no relative slidable movement between handle and rod is required, as is in the forms disclosed in Figs. 1 and 8. The hand-engaged operating means 32'' in this construction is thus used for adjusting the lamp on its arm and also the arm on its standard, without any need of grasping and soiling the shade; while the light herein is actuated by handling the element 19 on the switch 18 in the usual manner.

15 In Fig. 8 in this drawing my invention is shown as comprising a bracket arm 15', which is modified slightly from the above described arm 15, and it omits that casing or head 16 with its switch 18, being thus in a simple form and more economical in construction. However, this arm 15' also contains the depending stem 17' arranged to fit into the upper end of said customary standard 11, to be swingably adjustable thereon, like said arm 15. Otherwise the parts herein are identical with those in the above first described form and comprising the sleeve 21, which is also tiltably mounted by the screws 23 onto a knuckle 22' provided on the outer or free end of this arm 15'; the sleeve 21 being the same as in the preceding form, arranged to receive and carry the customary switch 27 with its pull-chain 28 and bulb 30 therein; while the hand-engaged means 32 herein likewise includes the rod 33 secured to pocket 35 on the sleeve and carrying the handle 36 slidably on said rod and engaged to the pull-chain 28, with this handle operable for actuating the switch and adjusting the lamp exactly as in the above described form. Only the arm 15' is herein modified at its standard-engaging end and the switch 18 is omitted, to economize and simplify this device whenever that is preferred.

I claim:

1. A control device for use on an electric lamp including an upright standard, said device comprising an arm and means at one end for readily mounting it adjustable in a horizontal plane on said standard, a sleeve mounted adjustably on the other end of said arm, an electric light socket including a pull-chain switch removably mounted on said sleeve, a rod having its upper end secured to the sleeve and depending therebelow, and a handle movably mounted on the lower end of said rod and being connected with the pull-chain, wherewith, by merely grasping and moving said handle the switch can be actuated and the socket with its light can be variously adjusted relative to said standard.

2. In an electric lamp including a hollow standard equipped with an electric conductor therein, a device comprising a hollow arm having means at one end mounting the arm swingably adjustable on the standard, with the conductor extended thru the arm, a sleeve tiltably adjustable on the other end of said arm and having a depending stem, an electric light socket including a pull-chain switch removably mounted on said stem and being operably connected with said conductor, a rod secured to and 75 depending from said sleeve, and a handle slide-

bly mounted on the lower part of said rod and being engaged to the pull-chain, wherewith, by sliding the handle on the rod said switch can be actuated and by moving the handle and rod said sleeve and light can be variously adjusted.

3. In an electric lamp including an upright standard having a bracket arm swingably adjustable thereon, means mounted as a unit and movable on the outer end of said arm and comprising a sleeve adjustable in a vertical plane on the arm, a bulb-receiving socket mounted on said sleeve and including a pull-chain switch, a rod depending from the sleeve, and a handle on the lower end of the rod and engaged to the pull-chain, said handle being movable on the

10

15

rod for actuating the switch and movable with the rod for adjusting the sleeve and bulb relative to the arm and to the standard.

GEORGE SCHASER.
